UNITED STATES PATENT OFFICE.

EDWARD A. BANSCHEACH, OF CHICAGO, ILLINOIS.

BINDING AND FILING DEVICE.

Application filed November 11, 1918, Serial No. 261,970. Renewed December 18, 1920. Serial No. 431,785.

To all whom it may concern:

Be it known that, I EDWARD A. BANSCH-
BACH, a citizen of the United States, residing
at Chicago, in the county of Cook and
5 State of Illinois, have invented certain new
and useful Improvements in a Binding and
Filing Device, of which the following is a
specification.

This invention relates to a loose leaf
10 binding and filing device which is made
readily accessible both for examining the
different sheets as they are held in a binder
or container, and for rendering the sheets
readily insertable and removable from the
15 different holders. The device may be also
used as a ledger sub-divider and marker,
and for otherwise facilitating the keeping
of accounts and records and rendering them
readily accessible when desired. To the
20 attainment of these ends and the accom-
plishment of other new and useful objects,
the invention consists in the features of
novelty in the construction, combination and
arrangement of the several parts.

25 Other objects will appear hereinafter.

In the accompanying drawings—

Fig. 1 is a side elevation of a sheet holder
or binder constructed in accordance with the
principles of the invention;

30 Fig. 2 is a sectional view of the same;

Fig. 3 is a detail section taken on line
3—3 of Fig. 2;

Fig. 4 shows one of the perforated locking
35 tongues of a sheet;

Fig. 5 illustrates a holder with a foot on
one side;

Fig. 6 illustrates a holder with the foot
formed as an extension of one of the covers;

Fig. 7 shows one of the covers provided
40 with a hook for engaging the cover of the
adjacent binding for elevating one side of
one of the binders more than the other;

Fig. 8 shows a plurality of binders con-
tained in a drawer;

45 Fig. 9 shows a modified form of binder;

Fig. 10 is a top view of a portion of a
containing drawer as shown in Fig. 8;

Figs. 11 and 12 illustrate a different
50 means for elevating one side of a binder;

Fig. 13 is a side view of a skeleton drawer;

Fig. 14 is a top view of the same;

Fig. 15 is a section taken on line 15—15
55 of Fig. 13; and

Fig. 16 is a detail showing the engage-
ment of one of the binder elevators as shown

by Figs. 11 and 12 with the track of the
skeleton drawer.

In any loose leaf binder or filing device
it is desirable not only that the separate
sheets or leaves may be easily removed from
and inserted in the binder, but also that the
leaves even when contained in the binder
may be rendered easily accessible even
though they and the binder itself are con-
tained in a drawer or other receptacle pro-
vided for holding them. The object, of
course, is to enable one to see at a glance
what is written or printed upon the card
or sheet so that one sheet can be quickly
distinguished from another in locating and
reading the desired sheet or card. In the
present invention it is proposed to provide
a loose leaf binder comprising a pair of
covers which may be used as a sub-divider
or for markers and to provide the covers 75
or the binder with means for tilting the
back thereof in such a way that one side of
the binder when contained in a flat drawer
or container will be raised above the other
side, thus separating the sheets in the binder
and rendering them freely accessible so that
they can be quickly thumbed by a person
who is searching for a particular card. The
advantage of this will be readily apparent
to any one who has ever attempted to select a
single card or sheet from others of the same
kind and size in a common container.

In the present invention the sub-divider
or binder may consist of a simple holder, as
illustrated more clearly in Figs. 9, 11 and 90
12, comprising a stiff back 1 with covers 2
hinged thereto and formed of the same or
other suitable material, preferably thin sheet
metal. At the ends of the back small tri-
angular pieces 3 are freely hinged which
95 are adapted to swing downwardly, as shown
more clearly in Fig. 5, when the binder as
a whole is raised from the base of any con-
tainer in which it is held. It is obvious
that when these small triangular pieces are
100 swung downwardly that they will raise one
side of the holder relatively to the other
one so that the upper or outer edges of a
number of sheets 4 contained in the holder
will be correspondingly inclined and there-
fore separated so that they can be quickly
105 thumbed for examining the sheets in the
well-known manner.

A simple expedient to accomplish the
same result is shown more clearly in Fig. 8 110

and comprises a wedge-shaped piece of material 5 which is disposed at the front end of a drawer 6 in which a number of holders are contained. When any one of these 5 holders is moved upwardly on the inclined block 5, the upper edges of the sheets 4 in the holder will be correspondingly inclined so that they can be readily separated and easily examined, as desired.

10 Instead of having a solid drawer, as illustrated in Fig. 8, a skeleton drawer 7 may be provided, which is much lighter and practically as strong as a solid drawer made of the same material. This drawer has bottom 15 pieces 8 which carry small channels or grooved rails 9 which are adapted to engage the small triangular pieces 3 at the ends of the holder, illustrated in Fig. 12. It will be observed that one of these rails 9 is close 20 to the left-hand side wall of the drawer, as viewed in Fig. 15, while the other rail 9 is at some little distance from the right-hand wall so that the holders will be spaced, as shown more clearly in Fig. 10, when contained in a 25 skeleton drawer, as well as in a drawer of the type shown in Fig. 10. The object of this is to provide a space at the right hand edge of the holders so that certain of the sheets 4 may be moved outwardly in that 30 direction, if desired, to separate them from the other sheets of the holder. It will be observed furthermore that by providing this space at one side only of the drawer it is more easily possible to register the hinged 35 triangular pieces 3 with the grooves of the rails 9 for the holders can be simply raised until the triangular pieces hang downwardly and that by pressing the holder to the left-hand side of the drawer the triangular 40 pieces will register with the groove rails 9 at each side of the drawer. When the holder is moved sideways in the drawer, after being thus elevated, the hinged pieces 3 will fold under the holder and allow the holder to 45 rest flat upon its back in the drawer.

It is also contemplated that the back of each holder may be formed with perforations through which a tongue 10 of a sheet 11, as shown by Fig. 4, may be inserted, the 50 tongue itself being formed with a slot 12 which registers with the slots of other sheets. At the bottom of such a holder there is provided a clamping device having a back 13 which extends over the edges of 55 the tongues 10 and having cooperating hinged members 14 and 15 with overlapping tongues 16 adapted to be inserted through the slots 12 of the sheets after the tongues 10 are inserted through the back of the 60 holder. These members 14 and 15 may be provided at their outer ends with cooperating notches 17 which will snap together when the tongues 16 are inserted through the slots 12 of the sheets, but may be released 65 by pressing the outer ends of the

members 14 and 15 and moving the notches apart. It will be observed that this clamping device forms a protecting back and cover which extends over the back proper of the holder itself and thus protects the tongues 70 10 of the sheets 11 which project through the back of the holder.

It is contemplated that either or both of the covers of the binders which have been described may be provided with a projecting hook or lug 18 near the outer edge, as illustrated in Fig. 7, which is adapted to engage the upper edge of the adjacent cover or the binder next to it so that it will be held raised above the other cover which is 80 not so hooked over the adjacent binder, as illustrated in Fig. 7, which will incline the holder and correspondingly incline the upper edges of the sheets contained in the holder. Also, instead of having a hinged 85 piece, as shown more clearly by Figs. 11 and 12, the back 19 of a holder, as shown by Fig. 5, may be provided with a rigid foot 20 which raises one side of the holder above the other; or one of the covers 21 may be 90 formed with an extension 22, as shown by Fig. 6, which will also accomplish the same result. In all of these constructions it will be observed that the object is to elevate one side of the holder above the opposite side 95 thereof so that the edges of the sheets will be separated from each other to facilitate in thumbing them.

It will be apparent that with this construction the binders or holders themselves 100 may be used as sub-dividers, and, of course, indexing sheets may be provided in the holders or binders themselves, which is common practice, to separate or designate subdivisions in the binders, as the covers of the binders preferably extend slightly beyond the edges of the sheets contained therein. The separate binders are readily removable from a drawer or receptacle containing a 105 number of them, and the sheets are separately removable from the binder or holder. Each separate binder or holder is easily accessible while contained in the common drawer or receptacle and each sheet can be examined without actually removing the 110 binder in which it is contained from the receptacle.

In using the binding device, as shown by Figs. 1 to 4, it is not intended that the clamping device shall be used on each of 115 the holders when they are contained in a drawer. Of course they may be applied to each one of the holders, but the clamping device is particularly designed and intended to be applied to the holder when it and the 120 sheets contained therein are withdrawn as a whole from a containing drawer. When 125 holders are placed in the containers without clamps the backs of the holders rest on raised rails, such as the channels 9 in Figs. 130

14 and 15, and thus the tongues 10 are held above the bottom of the container. Also, in order to space a holder of this type at one side of the drawer, as illustrated in Fig. 10, 5 the clamping device at the back of such a holder may be formed somewhat longer than the holder to which it is applied, as with an extension shown in Fig. 1, at one end thereof. This will insure that there is a 10 space at one end of the binder or holder in which the cards or sheets for posting may be offset or set out at one side, as shown in Fig. 10.

I claim:—

- 15 1. In a binding and filing device, a container, a plurality of loose leaf holders arranged in said container and free to be lifted therefrom, each holder having the sides thereof arranged to rest normally at the same level, and means for raising one side of 20 each holder more than the other side thereof.
2. In a binding and filing device, a loose leaf holder having a back and covers hinged thereto and adapted to rest on the back, a 25 flat bottom container for accumulating a plurality of said holders and means for raising one side of a holder, while in said container, a greater distance from the bottom of said container than the other side of said holder.

- 30 3. In a binding and filing device, the combination with a plurality of loose sheets, of a binder therefor comprising a back upon which the binder is adapted to rest and hinged covers at the sides thereof, and means for raising one side thereof more than the other.

- 35 4. In a binding and filing device, the combination with a plurality of loose sheets, of a holder therefor having a back upon which the holder is adapted to rest and covers pivoted thereto extending in an upright directions, and means for inclining the back so that one of the covers is raised more than the other, thus correspondingly separating the upper edges of sheets contained in the holder so that they may be easily separated in thumbing them.

- 45 5. In a binding and filing device, a loose leaf holder having a back and covers hinged thereto, the holder normally resting upon the back and the covers extending upwardly therefrom, and means for raising one edge of the back at will to thereby elevate one 55 cover above the other and to correspondingly incline any loose leaves contained in the holder so that they will be separated at the upper edges thereof.

- 60 6. The combination with a plurality of loose sheets, of a binder or holder therefor, and means separate from the holder for engaging the edges of the sheets to secure them in the holder or to secure them to one another independently of the holder.

- 65 7. The combination with a loose leaf

holder having a back and hinged covers, of a plurality of loose sheets adapted to be contained in the holder and projecting through the back thereof, and means for engaging the edges of the sheets which project through the back of the holder for binding the sheets together in the holder.

8. The combination with a loose leaf holder comprising an apertured back, of a plurality of sheets having projections extending through the apertures of said back and adapted to be contained in the holder, and removable means for engaging the projecting portions of said sheets to bind them together and to prevent them from becoming disengaged from the holder.

9. The combination with a loose leaf holder having a perforated back, of a plurality of sheets adapted to be contained in the holder and having slotted tongues which project through the opening in the back, and removable means engaging in the slots of the said leaves for binding the leaves together and for preventing their removal from the holder.

90 10. The combination with a loose leaf holder comprising a back with openings therein and hinged covers, of a plurality of sheets having projections which extend through the openings in the back, means for raising one of the covers relatively to the other for correspondingly inclining the back and the sheets contained in the holder, and a clamping device having means for engaging the projecting portions of the sheets for 95 binding them together and preventing their removal from the holder.

11. In a binding and filing device, the combination with a loose leaf holder having a back and covers hinged thereto, of a receptacle wider than the length of the holder in which the holder rests upon its back with the covers extending upwardly therefrom, a plurality of loose sheets adapted to be contained in the holder but separately removable therefrom and movable endwise in the space of the receptacle at one end of the holder, and means for inclining the back of the holder at will to elevate one cover there-of more than the other so that the sheets contained between the covers will be correspondingly separated to facilitate thumbing them.

115 12. In a binding and filing device, a loose leaf holder having a perforated back upon which it is adapted to rest, a plurality of loose sheets having projections insertable through the perforations of the back of the holder, a receptacle in which said holder is placed with the free edges of the sheets disposed uppermost, means for inclining the back of the holder at will in the receptacle to separate the upper edges of the sheets for thumbing them, and a removable binding device for engaging the projections of the sheets which extend through the perforations.

rations for holding the sheets together and for preventing their removal from the binder.

13. In a binding and filing device, a loose leaf holder having a back and covers hinged thereto, a plurality of loose sheets adapted to be contained in the holder, a skeleton drawer comprising an upper confining rail and a pair of bottom supports upon which the back of the holder rests with the covers extending upwardly therefrom, and means

operable at will while the holder is contained in the drawer for raising one cover of the holder relatively to the other cover, so that the upper edges of sheets contained therein will be correspondingly raised one above the other so that they can be easily thumbed for separating them.

In testimony whereof I have signed my name to this specification on this 8th day of November A. D. 1918.

EDWARD A. BANSCHBACH.
